CIGARETTE PACKAGE

Harry J. Anderson and Harry K. Deike,
Chicago, Ill.

Application February 11, 1939, Serial No. 255,828

9 Claims. (Cl. 206—48)

This invention relates to packages and particularly to cigarette packages having matches incorporated therein.

Numerous attempts have been made to devise ways for including matches within the package of cigarettes itself, none of which to our knowledge have been commercially successful.

It is an object of this invention to provide cigarette packages in which matches are incorporated in such manner that the bulk of the package is not substantially increased.

Another object of the invention is to provide a cigarette package from which matches may be separately removed without exposing the remaining matches in the package.

A further object of the invention is to provide an economical method for incorporating matches in a cigarette package.

Still another object of the invention is to provide a cigarette package in which matches are incorporated in such a manner that the package need not be mutilated to any substantial extent in order to remove matches therefrom.

These and other objects of the invention will be revealed by the following description and the accompanying drawing of which

Figure 1 is a perspective view of a package in accordance with the invention with a small portion of the package removed.

Figure 2 is another perspective view of the invention with the portion of the cover overlying the matches torn away.

Figure 3 is a diagrammatic elevational back view of a package in accordance with the invention with a portion removed.

Figure 4 is an enlarged cross-sectional view taken on the 4—4 of Figure 3; and

Figure 5 is a fragmentary plan view of a modification of the invention.

Referring to the drawing, the numeral 1 indicates generally a package of cigarettes of the general type now being widely marketed in which the cigarettes, usually twenty in number, are first wrapped in metal foil, such as tin, lead or aluminum or alloys thereof, lined with wax or other moisture-proof paper. This wrapping is indicated by the numeral 2, Figure 4. Immediately outside the metal foil wrapper 2 is a paper wrapper 3 upon which generally appears advertising matter. In recent years it has become common practice to apply a moisture-proof transparent wrapper such as Cellophane over the paper wrapper or cover. The transparent wrapper is indicated by the numeral 4. In order to simplify the explanation of the invention, Figures 1, 2

and 3 are illustrated without the transparent wrapper while Figure 4 is shown therewith. Thus far we have described a conventional package of cigarettes.

5 Our invention resides in the particular manner in which matches are incorporated in the package. The outer or paper cover 3 is perforated along horizontal spaced parallel lines 5 and 6 intermediate the top and bottom of the package. The lines 5 and 6 are connected by a series of spaced parallel vertical lines defining a series of small rectangular areas 11, 12, 13, 14, 15, 16, 17, 18, 19 and 20 surrounded by perforations. The wrapper or cover 3 is also perforated along a horizontal line 22, parallel to line 6 and spaced a short distance below it. The perforated lines 5, 6 and 22 extend to the side edges 23 and 24 of the package. The side edge 23 is perforated between the lines 5 and 22 as shown at 25 and the side edge 24 is likewise perforated between the lines 5 and 22 as shown at 26.

A match is glued to the underside of each of the perforated areas 11—20 as indicated by the numeral 27 (Figure 4). The matches are indicated generally by the numeral 28. As shown in the drawing, the matches are placed in the package in the same direction as the cigarettes and are slightly spaced from each other. The matches are preferably of the nature of those commonly marketed in small paper packages and made from paper or cardboard. Matches of this type are relatively flat and do not add any substantial bulk to the cigarette package. The matches 28 may readily be cut and separated at the time 25 the matches are applied to the cover or stamped out of a piece of paper or cardboard as a unit or strip. The matches are preferably stamped out of the cardboard or paper in such manner that the matches are spaced apart a distance 30 equal to the width of the match stem and the unheaded ends of the matches remain joined to a strip of cardboard or paper. The matches may be severed from the strip that holds them together just prior to or at the time the matches 35 are caused to adhere to the small areas on the cover surrounded by perforations. The manner of preparing the match strip and the particular manner in which the matches are severed from the strip do not constitute a part of the invention 40 claimed herein.

The strip of matches 28 consisting of ten matches—or half the number of cigarettes in the package—is placed against the inner side of the cover 3 prior to wrapping it around the cigarettes 55 so that the matches are properly placed with re-

gard to the perforated areas 11 to 20. Glue or other adhesive is first applied to the area defined between the perforated lines 5 and 6 and the matches then applied thereto with sufficient pressure to cause them to adhere to the adhesive. As previously stated, it is preferable to apply matches as a unitary strip and to sever the matches from the strip at the time or immediately before the matches are glued to the cover. It will be understood that the matches are so spaced and the areas 11 to 20 are of such size that a single match adheres to each of the areas. The perforated lines 5, 6 and 22 are spaced a sufficient distance from the top of the package so that the area defined between lines 6 and 22 will be directly over the lower ends of the matches when the match heads are adjacent to the top of the package. It will, of course, be apparent that individual matches may be glued to the inner face of the cover instead of applying the matches as a strip.

A second row of ten matches indicated generally by the numeral 41 is arranged in the lower half of the packages in the same manner as the matches 28. The outer or paper cover 3 is also perforated along spaced horizontal lines 45 and 47 adjacent the bottom edge of the package, the perforations extending to the side edges 23 and 24 of the package. A series of spaced, vertical, parallel, perforated lines join the lines 45 and 47 and define a series of areas 48, 49, 50, 51, 52, 53, 54, 55, 56 and 57. The wrapper 3 is also perforated along the line 59 (Figure 3) adjacent the bottom edge of the package and extending to the side edges 23 and 24. The edges 23 and 24 of the wrapper 3 are perforated between the perforated lines 45 and 59 as indicated at 61 and 63. A single match is caused to adhere to each of the areas 48 to 51 by applying glue or other adhesive to the under face of these areas and lightly pressing the matches 41 thereto in the same manner as described in connection with matches 28. Each match will adhere as shown at 65 to a single area surrounded by perforations.

It will be apparent from the drawing that the matches 41 are arranged so that the lower ends of the matches lie directly under the strip of the cover defined between the perforated lines 47 and 59.

A suitable friction surface or abrasive 67 on which to strike the matches may be glued or otherwise fastened to the bottom of the package on the outer surface of the cover.

When it is desired to open the package and smoke the cigarettes, the Cellophane or other transparent cover 4—if the package has such a covering—is entirely removed. The top of the package is then opened in the customary manner by breaking the revenue stamp and opening the foil in order to gain access to the cigarettes. The outer wrapper 3 is permitted to remain intact until a match is desired. At this point it is merely necessary to insert the finger nail in one of the perforated lines 25, 26, 61 or 63. Some may prefer to open from the left side while others may prefer to start from the right side. By thus inserting the nail, the perforation is broken, freeing one end of the strip defined between the perforated lines 6 and 22 or between 41 and 59. The free end of the strip is grasped by the fingers and the strip torn away from the package exposing the lower ends of the matches as shown at 69, Figure 1. Care should be exercised in tearing away the strip so that the adjacent areas

defined between perforated lines 5 and 6 or 45 and 47 are not torn loose.

After having removed the strip and having exposed the ends of the matches, an end match 5 is grasped between the fingers and given a slight downward pull or jerk. The match will be readily detached from the package and take with it only that small area of the cover bound by perforations to which it is glued. Thus if the 10 lower right hand match is first removed, it will remove with it only the area 57. When the next match is removed it will take with it only the area 56 to which it is glued, and so on. After the entire strip of matches is used, access is 15 gained to the matches in the second strip in the same manner as to the first.

It will be seen that by our invention a package is provided in which the matches do not come in contact with the cigarettes in the package and 20 cannot, therefore, taint the cigarettes. Furthermore, the matches are at all times substantially

covered so that moisture and perspiration do not get in contact with the heads and there is no likelihood of the matches accidentally rubbing against an extraneous surface. The package remains substantially intact since it is not necessary to tear the paper cover to obtain access to the matches nor is the package torn or mutilated during removal of the matches. The matches 25 add very little, if any, additional bulk to the package so that it is not necessary to change the size or shape of either the wrappers or the package. This is particularly true if matches with flat heads, which are not substantially thicker than the match stems, are used.

The invention readily adapts itself to current types of cigarette packages since it is merely necessary by a single operation to perforate the wrapper along appropriate lines, apply the adhesive to the areas to which the matches are to 40 adhere and then apply the match strips thereto.

As shown in Figure 3, the strips of the cover 3 defined between the perforated lines 6 and 22 and between perforated lines 47 and 59 may, if 45 desired, be perforated by spaced vertical lines defining areas corresponding to the areas 11 to 20 and 48 to 57. By perforating the strips in this manner it is not necessary to remove the entire strip when access is desired to the matches. Only that area need be removed which overlies the end of the match to be removed. The 50 numeral 70 indicates the portion of the cover which has been removed in order to remove five matches from the package.

Figure 5 illustrates another modification of the invention in which the small areas 71 to 80 and 81 to 90, to which the matches adhere, are triangular in shape instead of rectangular. It will be understood that the invention is not limited to the package illustrated and described 55 but is intended to broadly include match packages in which the matches are caused to adhere to small, easily detachable areas of the wrapper so that the matches may be removed without opening the wrapper or materially mutilating it. It will be apparent that the matches may be placed in the front of the package as well as in the rear. It will, of course, be apparent that the matches will be placed on a portion of the cover intermediate the edges. Thus, if the ends of the cover are sealed at the 60 back of the package, the matches will be placed under the cover on the front of the package. If the ends of the cover are brought together and sealed on the side of the package, the

matches may be placed on either the rear or the front of the package. The printed matter on the cover is not defaced by the perforations.

More or less matches than ten can be placed in the package and the matches may be differently arranged. For example, both strips of matches may be placed in the package so that the head ends of the matches are at opposite ends of the package. The perforations on the cover would have to be rearranged accordingly. Furthermore, the matches could be made in one strip and placed in a direction perpendicular to the direction of the cigarettes and the location of the perforated lines placed accordingly. However, the arrangement shown and described is preferred because it provides the maximum amount of room without materially adding to the bulk of the package and provides the most facile arrangement for removing matches.

What we claim is:

1. A cigarette package comprising an inner wrapper, an outer wrapper, a plurality of relatively small areas on said outer wrapper, each of which is defined by weakened lines or perforations, and a plurality of matches between said inner and outer wrappers, each of said matches adhering to a single one of said areas.

2. A cigarette package in accordance with claim 1 in which said outer wrapper is formed with a section defined by weakened lines or perforations, contiguous to said small areas and overlying the ends of the matches.

3. A cigarette package comprising an inner wrapper, an outer wrapper, a series of contiguous areas on said outer wrapper defined by weakened lines or perforations, a strip contiguous to each of said areas, also defined by weakened lines or perforations and a plurality of matches between said wrappers, each match adhering to a single area and so arranged that the ends thereof underlie said strip.

4. A substantially rectangular-shaped cigarette package comprising an inner wrapper and an outer wrapper, a series of contiguous rectangular areas on said outer wrapper defined by weakened lines or perforations extending in a straight line between opposite edges of the package, a strip immediately adjacent said areas also defined by weakened lines or perforations, a plurality of

matches between said wrappers, each of the matches adhering to a rectangular area and being arranged so that the ends thereof underlie said strip.

5. A cigarette package comprising an inner and an outer cover, a row of relatively small areas on said outer cover defined by weakened lines, a second row of relatively small areas defined by weakened lines adjacent to said first row, a plurality of matches between said covers glued to the small areas in one of said rows, the matches being arranged so that the ends thereof lie directly beneath the small areas in the other of said rows.

10 15 6. A cigarette package in accordance with claim 3 in which the small areas are triangular-shaped with the apices thereof pointing toward the heads of the matches.

7. A cigarette package comprising an inner 20 moisture-proof wrapper, an outer paper wrapper, a plurality of relatively small, triangular-shaped contiguous areas on said outer wrapper, each of said areas being defined by weakened lines and the bases of said areas being coincident, a strip 25 on said outer cover immediately adjacent the bases of said triangular-shaped areas, said strip being defined by weakened lines, and a plurality of matches between said inner and outer covers, said matches being glued to said small areas with the unheaded ends thereof lying underneath said strip.

8. A cigarette package in accordance with claim 1 in which said outer wrapper is formed with a section defined by weakened lines or perforations, 30 overlying the ends of the matches.

9. A substantially rectangular-shaped cigarette 35 package comprising an inner wrapper and an outer wrapper, a series of small, contiguous areas on said outer wrapper defined by weakened lines or perforations extending between opposite edges of the package, a plurality of matches between said wrappers, each of said matches adhering to an area as above defined, another small portion of said outer wrapper defined by weakened lines or perforations, the unheaded ends of said 40 matches lying beneath said portion.
